UNITED STATES PATENT OFFICE.

CHARLES FREDRECK HOOFER, OF SPOKANE, WASHINGTON.

GASOLENE-LIGHTER.

1,116,281.

Specification of Letters Patent.

Patented Nov. 3, 1914.

Application filed January 27, 1914. Serial No. 814,699.

To all whom it may concern:

Be it known that I, CHARLES F. HOOFER, a citizen of the United States, and a resident of Spokane, in the county of Spokane and State of Washington, have invented a new and useful Improvement in Gasolene-
Lighters, of which the following is a specification.

My invention is an improvement in gaso-
lene lighters, and has for its object the pro-
vision of a light and compact device of the
character specified, capable of being carried
in the pocket and by means of which a wick
may be ignited by means of a spark struck
from a body capable of producing sparks
when abraded by steel, and wherein the
movement of a single element extrudes the
wick, strikes a stream of sparks in the di-
rection of the wick, igniting the same, and
wherein the wick when not in use is retained
in a closed receptacle.

In the drawings:—Figure 1 is a perspective view of the complete device, Fig. 2 is a longitudinal vertical section, Fig. 3 is a
section on the line 3—3 of Fig. 2, Fig. 4 is a longitudinal section of the wick holder, Fig. 5 is a perspective view of the holding
ring for the wick, and Fig. 6 is a vertical section of the same.

The present embodiment of the invention comprises a casing 1 of suitable form and of rectangular cross section, the upper end of the casing being beveled at one side as shown at 2, and the said beveled portion is provided with openings 3 and 4. The casing is closed with the exception of the opening, and a holder 5 is inserted in the opening 4, the said holder 5 having its inner end closed as shown at 6 in Fig. 3. The upper end of the holder 5 is provided with a pair of approximately parallel resilient arms 7, each of which near its upper end, is provided with an outward bend 8 and the free end of each arm is curved outwardly as shown at 9. A lever 10 is journaled between the arms, the said lever being of steel and having intermediate its ends an arc-shaped extension 11, whose free edge is corrugated or roughened, and if the lever is not of steel the said extension must be of steel. At the center of the arc upon which the extension is formed, the lever is provided with a pair of oppositely extending trunnions or bearing bosses 12, each of the said bosses engaging the outward bend or bearing socket 8 of the adjacent arm 7. The lever is thus pivoted for

rocking movement between the arms and the lever is an elbow lever, the two ends being arranged at an angle with respect to each other. The roughened edge of the extension 60 or steel 11 cooperates with a cylindrical body 11^a of material capable of giving off sparks when abraded, and the said body is supported in the holder 5 and normally pressed toward the extension or steel, by 65 means of a coil spring 12^a, the said spring being arranged between the lower end of the spark producing body and the closed end 6 of the holder.

The grip portion of the lever extends ap- 70 proximately parallel with the adjacent face of the casing, and a plate spring 13 is secured to the lever as indicated at 14 at one end, the opposite end bearing against the side of the casing, and normally holding the 75 lever in the position of Figs. 1 and 2. The upper or opposite end of the lever is provided with a hook 15, which engages an eye 16 connected with a head 17 of the wick holder. The said head is frusto-conical in 80 shape and fits within the opening 3 of the case, tightly closing the said opening when the lever 10 is in the position of Figs. 1 and 2. The opening 3 is also frusto-conical to fit the head, and a tubular extension 18 is 85 connected to the head in spaced relation by means of oppositely arranged arms 19. The extension is counterbored or annularly recessed as shown at 20 near its lower end to receive the wick fastener shown in Figs. 5 90 and 6. The wick 21 is passed upwardly through the curved tubular member 18 until the upper end thereof is between the arms 19, and the fastener 22 is in the form of a split ring, having inwardly extending struck 95 up barbs or spurs 23, for engaging the substance of the wick to prevent downward movement of the same. The fastener 22 is inserted in the counterbore or recess 20, and holds the upper end of the wick in the open- 100 ings formed between the arms 19. The rear- most of the said openings faces the contact point of the flint and steel.

In operation, the case 1 is partially filled with gasoline or like material, as shown at 105 24 in Fig. 2. It will be noted that the holder 5 is provided with a lateral flange 25 at its upper end (Fig. 2), which seats against the face of the beveled portion 2, and the casing may be filled through the opening 3 or by 110 removing the holder 5 and inserting the fuel through the said opening.

Preferably to fill the casing 1, the holder 5 is removed from the opening 4, merely by drawing the lever directly outward, the resilience of the arms 7 permitting the bosses 12 to disengage from the arms. The holder 5 may then be removed, and the gasoline inserted. To operate the device after the holder 5 has been replaced and the lever 10 engaged therewith, it is only necessary to swing the lever 10 in the direction indicated by the arrows in Fig. 2. This movement withdraws the head 17 from the opening 3, and brings the openings between the arms 19 above the top of the casing 1. The same movement of the lever causes the steel or extension 11 to rub or grate against the outer end of the cylindrical body 11^a and throw a stream of sparks toward the upper end of the wick, thus igniting the same.

It will be noticed from an inspection of Fig. 3 that when the lever 10 is removed from the spring arm 7, the said arms will move toward each other a sufficient distance to prevent the cylindrical body being pushed out by the spring.

I claim:

1. A device of the character specified, comprising a casing for gasoline, said casing having a beveled upper end provided with spaced openings, a wick holding tube having a head fitting one of the openings for closing the same, said tube having an opening on the side adjacent to the other opening of the casing, a tubular holder in the other opening, said holder having means for engaging the beveled surface to limit the inward movement of the holder, a cylindrical body capable of giving off sparks when abraded in the holder, a spring pressing the cylindrical body outward, said holder having resilient arms, each arm having a bearing boss on its inner face near its upper end, the free ends of the arms diverging from each other, a lever between the arms, said lever having bearing lugs detachably engaging the bosses and having at the cylindrical body an arc-shaped extension provided with a roughened edge for engaging the cylindrical body, said lever having one end connected to the head of the wick holding tube, and a spring engaging the other end and normally holding the lever with the head in the opening.

2. A device of the character specified, comprising a casing for gasoline, said casing having a beveled upper end provided with spaced openings, a wick holding tube having a head fitting one of the openings for closing the same, said tube having an opening on the side adjacent to the other

opening of the casing, a tubular holder in the other opening, said holder having means for engaging the beveled surface to limit the inward movement of the holder, a cylindrical body capable of giving off sparks when abraded in the holder, a spring pressing the cylindrical body outward, said holder having resilient arms, each arm having a bearing boss on its inner face near its upper end, the free ends of the arms diverging from each other, a lever between the arms, said lever having bearing lugs detachably engaging the bosses and having at the cylindrical body an arc-shaped extension provided with a roughened edge for engaging the cylindrical body, said lever having one end connected to the head of the wick holding tube, and a spring engaging the other end and normally holding the lever with the head in the opening.

3. A device of the character specified, comprising a casing having a plurality of openings in its top, a tubular wick holder normally in the casing and having a head fitting and closing one of the openings, said wick holding tube having an opening facing the other opening of the casing, a holder in the other opening, said holder being tubular and having spaced resilient arms at its upper end, a lever detachably pivoted between the arms and having one of its ends connected to the head of the wick holding tube, said lever having a roughened extension between the arms, a cylindrical body capable of giving off sparks when abraded in the holder, a spring normally pressing the cylindrical body toward the lever, and a spring holding the lever with the head in the opening of the casing.

4. A device of the character specified, comprising a casing having a plurality of openings in its top, a tubular wick holder normally in the casing and having a head fitting and closing one of the openings, said wick holding tube having an opening facing the other opening of the casing, a holder in the other opening, a cylindrical body capable of giving off sparks when abraded in the holder, a lever pivoted to the holder and detachable therefrom, one end of the lever being connected to the head, a spring engaging the lever for holding the head in its opening, said lever having a roughened extension for engaging the cylindrical body when the lever is swung on its pivotal connection.

5. A device of the character specified, comprising a casing having a plurality of openings in its top, a tubular wick holder normally in the casing and having a head fitting and closing one of the openings, said wick holding tube having an opening facing the other opening of the casing, a holder in the other opening, a cylindrical body capable of giving off sparks when abraded in the

holder, and a lever pivoted to the holder and detachable therefrom, one end of the lever being connected to the head, said lever having a roughened extension for engaging the cylindrical body when the lever is swung on its pivotal connection.

6. A device of the character specified, comprising a casing having a plurality of openings in its top, a tubular wick holder normally in the casing and having a head fitting and closing one of the openings, said wick holding tube having an opening facing the other opening of the casing, a holder in the other opening, a cylindrical body capable of giving off sparks when abraded in the holder, a steel pivoted to the holder and having a roughened surface for engaging the cylindrical body when the steel is swung, said steel being connected to the head of the

wick holder for withdrawing the wick from the holder when the steel is swung.

7. A device of the character specified, comprising a casing having a plurality of openings, a holder in one of the openings, a cylindrical body capable of giving off sparks when abraded in the holder, a steel pivoted to the holder and having a roughened surface for engaging the cylindrical body when the steel is swung on its pivotal connection, a wick in the casing, and a connection between the wick and the steel for withdrawing the wick from the other opening when the steel is swung.
